UNITED STATES PATENT OFFICE.

ERNST SCHELLHASS, OF BERLIN, GERMANY.

CONVEYER APPARATUS FOR FEEDING BARS OF METAL TO AND DELIVERING THE SAME FROM MACHINES.

992,264.

Specification of Letters Patent. Patented May 16, 1911.

Application filed July 11, 1910. Serial No. 571,479.

To all whom it may concern:

Be it known that I, ERNST SCHELLHASS, a subject of the German Emperor, and residing at Berlin, Germany, have invented 5 certain new and useful Improvements in Conveyer Apparatus for Feeding Bars of Metal to and Delivering the Same from Machines, of which the following is a specification.

- 10 The present invention relates to improvements in conveyers especially adapted for feeding bars of metal, or girders to a drilling or other metal working machine, and particularly to means whereby the articles to 15 be operated on by such machine are delivered or fed to such conveyer. In accordance with this invention a series of the articles to be transported by the conveyer are stacked upon a suitable stationary support arranged 20 at one side of the conveyer and means are provided by which said articles are successively removed from the stack and deposited on the conveyer, such means being controlled by a single hand lever.
- 25 In the accompanying drawings, Figure 1 is a front elevation of a conveyer such as hereinbefore referred to and means for delivering articles thereto embodying the present invention; Fig. 2 is a vertical transverse 30 sectional view through the conveyer and such feeding means; Figs. 3, 4 and 5 illustrate in elevation, plan and detail section the clutch mechanism employed for connecting the feeding devices with a driver; Fig. 6 35 illustrates a slight modification.

Referring to the drawings, 1, 2, designate a pair of supporting beams on which are arranged a series of transverse beams 3 constituting a stationary support for the 40 articles to be transported by the conveyer which in the embodiment of the invention illustrated are I-beams 4. As shown the members 3 of said support are arranged in an inclined position and provided at their 45 lower ends with upwardly projecting stops 5 against which the lower one of the series of beams 4 bears.

The particular form of conveyer illustrated comprises a series of rolls 20 mounted 50 on shafts 20^a supported by suitable uprights or standards and the several shafts are connected by chain and sprocket gearing so that articles deposited thereon will be carried toward a suitable metal working machine, 55 such as is conventionally illustrated at 21.

Between the aforesaid stationary support for the articles to be transported and said conveyer are pivotally mounted a series of arms 9 adapted to be held in the position shown in full lines in Fig. 2 to form an 60 inclined way or slide extending from said support to the conveyer and to rock about their pivotal support so as to deposit on the conveyer articles previously supported by them. As shown, said arms 9 are 65 mounted to rock about a shaft 8, which is supported in suitable bearings 7 provided at the upper ends of frame 6 and the lower end of each arm is adapted to be engaged by a suitable latch which acts to hold the 70 arm in the full line position, shown in Fig. 2. As shown, such latch consists of a lever 11 mounted to rock about an axis 10 and having its upper end 11^a extending longitudinally of the adjacent arm 9. In one 75 edge said lever 11 is provided with a notch 12 adapted to receive a pin or stud 13 projecting laterally from the adjacent arm 9 and said latch lever is so weighted and constructed that it automatically tends to engage the pin 13 and thus hold the lower end of the arm 9 against movement thereby providing a firm guideway over which the beams 4 can move.

The beams 4 are successively transferred 80 from the stationary support 3 to the inclined slide or guideway formed by the arms 9 by the action of a series of disks 22 secured to the shaft 8 and each having a cam shaped periphery providing a member 22^a 85 adapted as the shaft 8 rotates to engage a flange of the lowest beam 4 of the series and lift the same over the stops 5 and push it on to the slide 9. As the beam passes down the slide it will strike the upper ends 11^a 90 of the latches 11 with sufficient force to rock said latches and disengage the pins 13 from the notches 12. As soon as the arms 9 are thus released they will under the weight of the beam supported thereby rock downwardly about their axial support and the beam will thereby be deposited upon the conveyer rolls 20 in proper position to be fed to the machine 21. The shaft 8 is adapted to be clutched to a suitable driver by means 105 permitting it to make but a single revolution and then be automatically disconnected. This clutch mechanism and the means by which an operator can control the action thereof is illustrated particularly in Figs. 3, 110

4 and 5 referring to which it will be seen that the clutch 23, comprises a driving member 58 which may rotate constantly and a member 57 which is connected with the shaft 8 by means hereinafter more particularly described adapted to be engaged with said member 58 by the operation of a hand lever 24. Said lever 24 is pivotally mounted at 28 and near its upper end is provided with a latch member 48 having a link 49 terminating in a pin 49' that projects into a slot 49" in said lever and adapted as the latch is rocked to be moved to and from a position where it will engage with a shoulder 50 on a reciprocating member 51 having its end adjacent the shaft 8 bifurcated and terminating in two forked arms 54, 59, arranged respectively above and below the horizontal plane of said shaft. A stop 52 co-operating with a shoulder 60 on the slide 51 acts to normally hold said slide in the position shown in Figs. 3 and 4 in which position a pin 53 carried by an arm 55 secured on the shaft 8 engages the fork 54. The arm 55 is not connected directly to the shaft 8 but to a threaded sleeve 56 which is revoluble on said shaft and which threaded sleeve is engaged by the hub of the movable clutch member 57. By manipulating the latch 48 to move the pin 49' upwardly in the slot in the operating lever 24 and shifting said lever from the position I, Fig. 3, to the full line position II in said figure, the slide 51 can be rocked sufficiently to disengage the nose 60 thereon from the stop 52 and by then returning said lever to the position I, the arm 55 will be rocked and the clutch member 57 engaged with the driving member 58. The shaft will thereby be caused to rotate and through the disks 22 transfer a beam 4 from the stationary support to the inclined feed slide 9. As the shaft rotates the pin 53 on the arm 55 will be moved out of engagement with the fork 54 and will subsequently engage the lower fork 59, thereby moving the slide 51 in the reverse direction and bringing the projection 60 in front of the stop 52. The lever 24 is retained in the position I, it being understood that the latch 48 is released and the pin 49' returned to its original position as soon as the slide 51 has been disengaged from the stop 52 at the time of moving the lever 24 from position II to position I. The continued turning of the shaft 8 will carry the pin 53 from the fork 59 and into the fork 54 or the position shown in Fig. 3 and by the engagement of said pin with the latter fork the rotation of said arm 55 will be checked, the slide 51 being at this time held stationary by the action of the stop 52. Consequently the sleeve 56 will be turned sufficient to disengage the clutch members 57, 58, and the shaft 8 will be held stationary until the lever 24 is again operated.

In order not to interfere with the feeding movement of the beam 4 by the conveyer rolls, means are provided whereby the arms 9 and latch levers 11 are retained in the position indicated in dotted lines in Fig. 2, 70 which are assumed during the operation of delivering a beam to the conveyer, until said beam has been transported beyond the paths of movement of said arms and levers. The particular stop mechanism employed for 75 this purpose in the embodiment of the invention illustrated is designated as a whole by the reference character 15 and comprises two members 15^a pivotally mounted on a suitable axis 16 and provided respectively 80 with fingers or tappets 17, 18. Each of said stop members is so weighted as to automatically tend to assume the position indicated in Fig. 2 and a slot 30 is formed through the lower portions of said members 85 and into said slot extends a pin 29 on a swinging arm 27 which is connected by links 25, 26, with the lever 24 or the shaft 28 on which said lever is mounted.

Referring to Fig. 2, it will be seen that 90 when the beam 4 slides down the inclined guideway 9 and strikes the head 11^a of the latch lever 11, said lever will be rocked to carry a projection 19 thereon beyond and into engaging position with the tappet 18. 95 During the movement of the latch lever 11 from the position indicated in full lines in said figure to that represented in dotted lines, the tappet 18 will swing about the axis 16 but will immediately return to the 100 position shown in Fig. 2 and by reason of the pin 29 engaging the right hand side of the slide 30 will act to positively prevent return of the lever 11 to its full line position. Similarly the downward movement of the 105 arm 9 will rock the tappet 17 about the axis 16 and such tappet will automatically assume the position shown in Fig. 2 where the arm 9 is prevented from upward movement by reason of the engagement of the pin 29 with the right hand end of the slot 30 in the support for the tappet 17. The parts will be retained in this position while the lever 24 occupies the position I indicated. When, however, said lever is returned to position 110 II the pin 29 will be shifted to the opposite end of the slot 30 and the arms 9 can then return to their elevated position under the action of counter-weights 14 connected therewith and the latch levers 11 will also return to the position indicated in full lines in Fig. 2 in which they engage the pins 13 on said arms 9, as before described.

Instead of employing counter-weights 14 to return the arms 9 to the operative position, said arms may be positively rocked from the shaft 8, as illustrated in Fig. 6. In this construction the rearwardly extending member of each arm 9 is connected by a link *e* with an arm *d* of a bell crank lever 130

fulcrumed at *b* upon a bracket *a* on the standard 6. The other arm *c* of said bell crank lever extends into the path of rotation of a pin or stud *f* on the adjacent disk 5 22. Thereby as the shaft 8 is rotated to remove a beam from the stationary support the arms 9 are positively rocked upwardly into position to form the inclined feed guide and are retained in this position by the 10 latches 11 after the pin *f* has passed from engagement with the arm *c* of said bell crank lever.

Having thus described the invention what is claimed and desired to be secured by 15 Letters-Patent is,

1. The combination with a conveyer, of a relatively stationary support at one side of the conveyer, an inclined guideway between said support and conveyer, adapted to 20 move vertically relative to the conveyer, and a revoluble transfer device arranged to successively remove articles from said support and deliver them to the upper end of said guideway, said articles being deposited on 25 the conveyer by the movement of said guideway.

2. The combination with a conveyer, of a relatively stationary support extending longitudinally of the conveyer at one side 30 thereof, an inclined guideway between said support and conveyer, adapted to rock about a horizontal axis adjacent its upper end, and a shaft arranged between the support and guideway and provided with radially 35 projecting means adapted as the shaft rotates to engage an article on said support and transfer it to the inclined guideway, said guideway automatically rocking about its axis to deposit the article supported 40 thereby on the conveyer.

3. The combination with a conveyer, of a relatively stationary support extending longitudinally of the conveyer at one side thereof, an inclined guideway extending continuously 45 between said support and conveyer, and a shaft arranged between the support and guideway and provided with a plurality of disks adapted as the shaft rotates to positively engage and transfer an article 50 from said support to the inclined guideway.

4. The combination with a conveyer, of a relatively stationary support at one side of the conveyer, an inclined guideway arranged between said support and conveyer and 55 adapted to rock about a horizontal axis, and means independent of said guideway for automatically transferring articles successively from said support to the guideway, the latter rocking about its axis to deposit such articles 60 on the conveyer.

5. The combination with a conveyer comprising a series of feed rolls, of a relatively stationary support at one side of the conveyer, a plurality of pivotally mounted arms 65 adapted to form an inclined guideway be-

tween said support and conveyer, means for transferring articles successively from said support to said arms, and means for holding said arms in operative position until the article supported thereby is properly positioned above the conveyer and then automatically releasing said arms and permitting them to rock and deposit such article on the conveyer. 70

6. The combination with a conveyer comprising a series of feed rolls, of a plurality of arms pivotally mounted to rock about an axis at one side of and above said conveyer, said arms in one position forming an inclined guide for delivery of articles to the 75 conveyer, means acting to hold said arms in such operative position and adapted to be automatically released when an article supported thereby is in position to be deposited on the conveyer by a rocking of said arms about said axis, and means for restoring the arms to said operative position. 80

7. The combination with a conveyer comprising a series of feed rolls, of a plurality of arms pivotally mounted to rock about an 85 axis at one side of and above said conveyer, said arms in one position forming an inclined guide for delivery of articles to the conveyer, a pivotally mounted latch adapted to engage each of said arms to hold it in such 90 operative position and to be released by impact of an article sliding down said inclined guide, whereby such article will rock said arms and be thereby deposited on the conveyer, and means for restoring said arms to 95 such operative position. 100

8. The combination with a conveyer comprising a series of feed rolls, of a plurality of arms pivotally mounted to rock about an axis at one side of and above said conveyer, said series in one position forming an inclined guide for delivery of articles to the conveyer, a pivotally mounted latch adapted to engage each of said arms to hold it in such 105 operative position and to be released by impact of an article sliding down said inclined guide, whereby such article will rock said arms and be deposited on the conveyer, means for restoring said arms to such operative position, and means for preventing 110 such restoring movement. 115

9. The combination with a conveyer, of a relatively stationary support at one side of the conveyer, an inclined pivotally supported guideway between said support and conveyer, a rotary transfer mechanism for successively removing articles from the support and delivering them to said guideway, means for holding the guideway in position 120 to conduct articles to the conveyer and adapted to be automatically released when a rocking of the guideway will deposit the article supported thereby on the conveyer, and means for restoring the guideway to such 125 operative position. 130

10. The combination with a conveyer comprising a series of feed rolls, a relatively stationary support at one side of the conveyer, a plurality of pivotally mounted arms adapted to form an inclined guideway between said support and conveyer, a pivotally mounted latch adapted to engage each of said arms to hold it in such operative position and to be released by impact of an article sliding down said inclined guide, whereby such article will rock said arms and be de-

15
posited on the conveyer, means for restoring said arms to such operative position, and means for successively transferring articles from the said support to said arms.

In testimony whereof, I affix my signature in the presence of two witnesses.

ERNST SCHELLHASS.
